UNITED STATES PATENT OFFICE.

JOSEPH J. SAENGER, NICK SAENGER, AND MATH SAENGER, OF RHAME, NORTH DAKOTA.

BINDER HITCH.

Application filed April 20, 1925. Serial No. 24,486.

The present invention relates to a binder hitch and aims to provide a device which will compensate for side draft and with which it is possible to make a right angular 5 turn in either direction.

A still further object of the invention is to provide a device of this nature which is simple in construction, reliable in operation, strong, durable, and well adapted to the 10 purpose for which it is designed.

With the above and numerous other objects in view as will appear as the description proceeds, the invention resides in certain novel features of construction, and in 15 the combination and arrangement of parts as will be hereinafter more fully described and claimed.

In the drawing:—

Figure 1 is a top plan view of the improved binder hitch, and

Figure 2 is a section taken on line 2—2 of Figure 1.

Referring to the drawing in detail it will be seen that 5 designates generally the binder 25 which may be of any preferred construction.

The binder tongue 6 is attached to the binder as at 7 in the usual manner and is braced by the rods 8. The team tongue 9 is attached to the end of the binder tongue 6 in the 30 usual manner. The parts thus far described are all of conventional construction and are illustrated merely for the purpose of bringing out the advantages and utility of our invention.

35 Our improved structure consists of a bar 10 which is pivoted off center intermediate its ends as at 11 to the rear end of the tongue 6. The end of the shorter arm of this bar 10 has attached thereto a rod 12 which extends forwardly and is attached to the forward end of the tongue 6. A second rod 13 is pivotally engaged with the other end of the bar 10 and extends across the tongue 6. The forward end of this rod 13 has a plurality of links 14 mounted thereon with which is engaged a clevis 15. A plate 16 is mounted on a bar 17 which is held in place by bolts 18 and 18'. A reinforcement bar 26 has its ends engaged with the under side

of the plate 16 by bolts or the like while 50 its intermediate portion is spaced from the plate by the sleeves 28 on bolts 18 which pass therethrough. This bar 17 is pivotally engaged with the pivotal connection 25 between the tongues 6 and 9 and is provided 55 with a brace 19. The bar 20 is receivable on top of the plate 16 and extends over the bar 17 being held thereon by the bolt 18'. A three-horse evener 21 is pivotally 60 engaged with one end of the bar 20 while a two-horse evener 22 is attached to the other end thereof adjacent the team tongue 9. If a four-horse team were to be used, a two-horse evener would be substituted for the three-horse evener 21 and the bar 20 65 shifted so that the opening 23 would be pierced by the bolt 18'. It is evident that numerous adjustments of this kind can be made by those skilled in this art.

Our invention particularly includes the 70 bars 10 and 17 with the rods 12 and 13, and it will be seen that the pull on the rod 13 will tend to eliminate the side draft of the binder most effectively.

It is thought that the construction, operation, and advantages of the invention will 75 now be clearly understood by those skilled in this art. It will be apparent that numerous changes in the details of construction, in the sizes, in the materials, and in the 80 combination and arrangement of parts may be resorted to without departing from the spirit or scope of the invention as hereinafter claimed or sacrificing any of its advantages.

Having thus described the invention what 85 we claim as new is:—

A side draft preventing device for a binder, wherein the binder is provided with a tongue extending forwardly thereof and a second tongue pivoted to the end of the 90 first tongue, including a bar pivoted off center intermediate its ends to the rear end of the first tongue, a second bar having one end pivotally engaged with the pivot connection between the first and second tongues 95 to extend laterally therefrom, a rod attached to one end of the first bar and to the forward end of the first tongue, a second rod

attached to the other end of the first bar and crossing the first tongue, a member loosely engaged on the end of said second bar, a third bar detachably mounted on the 10
5 second bar, the intermediate portion of said third bar being pivoted to the free end of the second bar, draft appliances attached to said third bar, and said member loosely

attached to said third bar and said second bar.

In testimony whereof we affix our signatures.

JOSEPH J. SAENGER.
NICK SAENGER.
MATH SAENGER.
